UNITED STATES PATENT OFFICE.

FREDERICK T. RUSSELL, OF UTICA, NEW YORK, ASSIGNOR TO SAVAGE ARMS CORPORATION, OF UTICA, NEW YORK, A CORPORATION OF DELAWARE.

WASHING MACHINE.

Application filed October 5, 1926, Serial No. 139,765. Renewed January 3, 1928.

This invention relates to washing machines and in particular to the control of the wash water or whatever liquid may be used therein, one of the objects of the invention being to prevent an excessively high liquid level therein—in particular when more liquid, such as the rinse water, is added; another object being to remove sediment from the water and also to provide convenient means for the discharge of the liquid when such is desired.

5

In the accompanying drawings the invention is shown as applied to a washing machine of a well known construction, Fig. 1 being an elevation, partly broken away, of the complete assembly; Fig. 2 a horizontal section also broken away to facilitate illustration; Fig. 3 a vertical section of the constant level device; Fig. 4 a view, partly 20 sectional, of the tank and a disposal pump connected therewith; Fig. 5 a vertical section on the line V—V of Fig. 4, and Fig. 6 a view of a portion of the tank bottom, the pump attachment and the pump drive.

The washing machine to which the invention is shown as applied comprises generally a tank 1, a spinner or clothes cage 2 mounted for rotation therein and a driving motor 3. The liquid level in the tank is indicated in Fig. 1 and for washing, the spinner is tilted 30 to and rotated on an inclined axis, through a suitable drive from the motor 3 so that it dips beneath the surface. For drying the clothes, the spinner is rotated on a vertical axis (the position shown) where it is above the water level. In this position the clothes 35 may also be rinsed by adding or spraying the rinse water through the open top of the spinner, while the spinner is in rotation.

In the bottom of the tank is an outlet 4 which may communicate directly with the drain if the circumstances permit or otherwise may be connected, as shown, with an impeller pump 5. The latter may conveniently be driven from the motor, off the countershaft 6 through a sliding clutch member 7 splined to the pump shaft 8 and having a pin 9 adapted to engage the driver pin 10. In the drawings the driver is shown 45 as carried by the housing of the automatic clutch (not shown) which transmits the drive to the spinner. In the construction illustrated the pump is connected or disconnected by the friction lever 11 which is con-

veniently located for foot operation, as 55 shown in Fig. 1, although, as will be apparent, the clutch 7 and operating pedal may be omitted, the pump then being arranged to operate continuously but under no load unless liquid is being discharged 60 from the tank. The delivery side of the pump may be connected to any suitable point of disposal, Fig. 1 showing the machine located adjacent a sink 12 and the pump outlet 13 communicating therewith.

65 As stated above the clothes are rinsed by rotating the spinner on a vertical axis while the rinse water is added through the open top of the spinner, the rapid rotation of the latter forcing the liquid outwardly 70 through the clothes. The water already in the tank has of course been used for washing and to prevent the liquid level from rising and permitting this dirty water to come in contact with the clothes or to interfere with the subsequent drying operation, the tank is provided with the overflow device now to be described.

The tank outlet 4 is closed by a stopper 14 and passing through the stopper is the 80 lower end of an overflow pipe 15 which extends up into the tank to a height equal that of the constant level to be maintained. The stopper and overflow pipe are suitably connected together by threaded engagement 85 and to a stopper operating rod by means of the lock nut 16 and the stopper rod 17 is slidably mounted on the inner side of the tank wall and extends upwardly to a point adjacent the tank top where it can be easily 90 reached. A spring 18 acting on the rod urges the stopper to its closed position.

95 Enclosing the pipe 15 is an upflow pipe 19 also carried by the stopper rod 17 and extending from a point close to the tank bottom to a point above the desired constant level thereby ensuring that the water which passes out through the overflow will be drawn from the lower portion of the tank where the sediment and dirty water settle. The upper end of the upflow pipe is closed 100 except for the vent pipe 20 which prevents the two pipes from operating as a siphon and also assists in supporting pipe 19 on the stopper rod.

105 From the above the manipulation of the machine will be readily apparent, the pump 5 being under the control of the lever or

pedal 11 and the overflow device movable as a unit to effect the discharge of the entire contents of the tank.

It will be apparent that the construction shown serves as a check for the operator when introducing the wash-water in the first instance, tending to prevent an improperly high water level and that in the preferred form, which includes an upflow pipe such as 19, after the washing has been done it enables the dirty water settling at the bottom to be easily removed and substituted by fresh water, such as may be used for rinsing as above pointed out, and also that it keeps the level from rising so high as to impair the subsequent use of the machine. When the tank is to be completely evacuated the stopper rod is pulled up, which in the present case, also lifts the overflow pipe but it will be understood that the overflow and level maintaining effect is quite independent of the stopper and the latter could if desired be independently located, the overflow pipe in such case being fixed. The concentric arrangement of the upflow and downflow pipe is preferred because of compactness and economy of manufacture but the principle will be seen to be capable of incorporation in other and different forms all of which are intended to be covered by the following claims.

Claims:

1. The combination in a washing machine having a tank, clothes washing mechanism within the tank and a motor for driving said mechanism, of a pump also driven by said motor, an overflow pipe communicating at its lower end with the suction side of the

pump and extending upwardly into the tank to establish a constant level therein, a second pipe within the tank communicating with the upper end of the first and terminating at its lower end adjacent the tank bottom to limit the flow through said overflow pipe to liquid drawn from the lower portion of the tank, and vent means operative to prevent the siphoning action of said pipes and the removal by the pump, through the overflow pipe, of the entire liquid content of the tank. 40 45 50

2. In a household washing machine, the combination of a wash water tank, a motor, clothes washing mechanism within the tank driven by said motor, and means for controlling the wash water comprising a pump, 55 also driven by the motor, having a delivery pipe adapted to discharge wash water to a higher level, and a suction pipe for said pump having two intake openings within said tank, one of said intakes being at the 60 bottom of the tank and normally closed during washing and the other being an overflow passage having its entrance slightly above the bottom of the tank and adapted to establish a predetermined water level 65 therein above the level of said entrance and means for preventing siphoning of the wash water through said overflow passage, whereby continued operation of said pump evacuates said wash water from the lower 70 part of the tank and only to said predetermined level unless said first mentioned pump intake is opened.

In testimony whereof, I have signed this specification.

FREDERICK T. RUSSELL.
